Fig. 5

Fig. 6

Fig. 7

Fig. 8

Fig. 9

FIG. 1 is a perspective view of a floor cleaner or similar article, showing my new design;

FIG. 2 is a side elevational view of the cannister element thereof, shown without the cleaning head for ease of illustration;

FIG. 3 is a front elevational view thereof;

FIG. 4 is a top plan view thereof;

FIG. 5 is a bottom plan view thereof;

FIG. 6 is a side elevational view of the cleaning head, shown without the cannister for each of illustration;

FIG. 7 is a front elevational view thereof;

FIG. 8 is a top plan view thereof; and

FIG. 9 is a rear elevational view thereof.

The hose and cord elements have been fragmentarily shown in all views for convenience of illustration and to indicate indeterminate length.

I claim:

The ornamental design for a floor cleaner or similar article, as shown and described.
